UNITED STATES PATENT OFFICE.

HENRY A. VAN HOUTEN, OF BELLINGHAM, WASHINGTON.

PER-DIEM CAR-RECORD ACCOUNT CABINET AND CARDS.

1,191,857.

Specification of Letters Patent. Patented July 18, 1916.

Application filed March 17, 1914. Serial No. 825,338.

To all whom it may concern:

Be it known that I, HENRY A. VAN HOUTEN, a citizen of the United States, residing at Bellingham, in the county of Whatcom and State of Washington, have invented new and useful Improvements in Per-Diem Car-Record Account Cabinets and Cards, of which the following is a specification.

My invention relates to a card record system for use by railroads for keeping an accurate account of the per diem records of foreign cars or the cars of other roads present at any time upon the track system of the railroad employing the record system, the primary object of the invention being to provide an account record cabinet and cards whereby the disposition and condition, whether empty or loaded, of all foreign cars upon the tracks of a railway may be conveniently kept with a minimum amount of time and labor, and so that the per diem charges upon any car may be readily and quickly obtained at any time.

A further object of the invention is to provide an account record cabinet and cards which facilitate the operation of filling out, applying and removing the cards in enabling a record of any particular car to be ascertained at any time, and also by means of which the time and labor involved in keeping the records of this character by the ordinary system of bookkeeping may be considerably reduced.

The invention consists of the features of construction, combination and arrangement of parts herein fully described and claimed, reference being had to the accompanying drawings in which:

Figure 1 is a front elevation of a card record cabinet embodying my invention and employed in my record system. Fig. 2 is a top plan view of the same. Fig. 3 is a vertical front to rear section through the cabinet on the line 3—3 of Fig. 2. Fig. 4 is a fragmentary top plan view, showing a portion of the cabinet containing several card receiving pockets or cells on an enlarged scale. Fig. 5 is a sectional view thereof. Fig. 6 is a plan view of a series of record cards employed in the system made according to my invention. Fig. 7 is a detail view of one of the cards, showing the same made out to indicate items pertaining to the record of a particular car.

All railroads find it necessary to maintain a staff of clerks for the purpose of keeping a record of the presence, movements and condition, whether empty or loaded, of the foreign cars, or cars of other railroads, which are in transit or being employed upon the lines of the railroad in question, in order that the cars may be properly routed and accounted for, losses and car shortages prevented, and the per diem runnings of the cars obtained, claims for errors or damages avoided. This entails upon the railroad considerable labor and expense, in the employment of clerks, agents, etc., owing to the system of bookkeeping usually employed.

The particular object of my invention is to provide a record system by means of which an accurate record of the facts relating to all foreign cars may be kept in a much simplified manner, with greater certainty and convenience, and at a material saving in cost to the railroad.

In carrying my invention into practice I provide an account cabinet 1 which is provided at its upper rear portion with a bracket 2, by which the cabinet may be arranged upon a desk or other support in an inclined plane, so that the top or upper surface of the cabinet will slope at a desired degree. The cabinet is preferably of rectangular or oblong rectangular form and comprises a bottom 3, top and bottom walls 4 and 5 and side walls 6 and 7, the interior of the cabinet being divided by main and vertical transverse partitions 8 and 9 into a plurality of record sections or compartments 10. Each of these record sections or compartments 10 is further subdivided by vertical and transverse strips 11 and 12 to provide cells or pockets 13, arranged in vertical and transverse rows, and of which any desired number to each record section or compartment may be employed, one hundred cells or pockets in each record section or compartment being ordinarily used.

The cells or pockets of each section or compartment are all closed by the bottom 3, and are arranged at an upward and forward angle to the vertical, so that the entrances to the cells or pockets will lie at slightly different levels from top to bottom, sufficient to permit the head portions of record cards inserted therein to project in successive tiers, one above the other, so that such head portions of the cards may be readily and conveniently viewed and distinguished from the front of the cabinet. By thus constructing and mounting the cabinet, a proper slope or inclination of the pockets or cells is secured for the purpose described without the necessity of cutting off the top of a horizontal cabinet at an angle or otherwise making a cabinet of cumbersome and expensive construction. The cells or pockets of each record section or compartment are consecutively numbered from 1 to 99 in any convenient manner, the lower row of cells being numbered 1 to 9, inclusive, the next row of cells from 10 to 19, inclusive, and so on throughout the series. This may be understood, or the numbers of the cells may be marked in any convenient manner upon the walls thereof. For the purpose of enabling the location of a cell of any particular number to be quickly ascertained when the cells are filled or partially filled, the marginal walls of each section or compartment are provided with indications along two of the sides thereof, in alignment with the vertical and transverse rows of cells. In the present instance, for purposes of example, indications of the character described are shown along the bottom and one of the sides of one of the sections or compartments 10, each set of indications consisting of the digits, beginning with "0" and ending with "9", the arrangement being such that by following out the numerals in the two sets of indices the location of a cell or pocket bearing any particular number may be quickly and conveniently ascertained. Thus if it is desired to determine the location of pocket No. 46, by following up the vertical row from the numeral 4 in the lower row of indices until it intersects the cell or pocket in line with the numeral 6 of the vertical row 40 of indices, the location of pocket 46 will be evident as it falls at the intersecting point.

In conjunction with the cabinet, constructed as above described, I provide cards or slips 14, made of paper or other suitable material. Each of these cards has its face portion imprinted to provide a form for the reception of any desired indicating matter relating to the number, condition and movements of a car whose route, etc., is to be kept track of. As shown in the present instance each card is provided with two transverse subdivisions at the top or head portion, one being designated "No.", to receive the number of the car, and the second 55 being denoted by the word "Initial" to receive the name of the foreign road to which the car belongs, or its abbreviations. Below the head space the card is provided with three vertical columns 15, 16 and 17. The first column 15 is transversely divided at top and bottom to provide spaces in which respectively appear the word "Routing" and the words "Del'rd to" to receive matter indicating the line of routing and 65 the title of the road to which the car is finally delivered. In the body of the column 15 may be placed any appropriate signs, symbols or other matter indicating in regular order the conditions of the car at different times. In the central column 16, which is provided at the top with the heading "Disposition," may be inserted the matter opposite the insertions in the column 15 relative to the location or disposal of the car at any time, and in the column 17, which is appropriately headed "Date", will be placed opposite the items in the columns 15 and 16 the dates on which said items were entered. The bottom of the card is transversely divided to provide a footing space 18 designated "Total per diem", in which may be placed the final statement of the number of days for which there is a per diem charge, indicating the time the car has been en route or employed on the road in question and the sum total to be paid in earnings to the railroad owning the car. For convenience in enabling the time periods of use of various cards or slips to be determined by a casual inspection of those within the cabinet or rack, different colored cards may be employed for different month periods. For instance, as shown in Fig. 6, a series of cards 19, 20, 21, 22, 23 and 24, six in number, but which are differently colored, may be used for each six months' period of the year, beginning with January and ending with June, and then beginning again with July and ending with December. Thus foreign cars which remain from one month to another on the lines of the railroad may be detected at a glance, so that where there is any apparent unusual length of stay, the accountant may inspect the card to determine all facts relating to the case, and send the car forward on its route if it has been unduly detained.

In employing the system in practice, it may be found convenient to arrange all the cards relating to the cars of a particular foreign road in one of the sections or compartments 10 of the cabinet, particularly where a large number of cars of such foreign road are constantly upon the tracks of the railroad keeping the account system, and if there are several such foreign roads each one may be given a separate section or compartment, and one or more other compartments provided for general use in keeping an account of the cars of other roads. It will, of course, however be understood that there may be but a single section or compartment common to all foreign roads, according to the manner in which the account system is conducted by the railroad using it. It is found convenient and desirable in classifying the cards, to use the last two figures of the number of the foreign car whose record is to be kept as the designating numeral of the pocket in which it is placed.

Thus for instance if the record card of a foreign car No. 4457 is placed in one of the cells or pockets 13 of any compartment 10, it will be placed in the cell or pocket of such section 57. This obviates the necessity of giving upon each card not only the number of the car, but also a distinguishing number for the card, simplifies the classification of the cards and also avoids confusion. By 13 this mode of indication and classification of the cards in the pockets, the necessity of employing a large cabinet or rack for keeping even a large number of cards is avoided, since a very large number of cards may be 15 stored within a cabinet rack containing a comparatively small number of pockets.

It will be understood from the foregoing description that the accountant on receiving the first record of a foreign car makes out a 20 card and fills in the initial information matter, and then as subsequent reports are received the items are entered upon the card, which is placed in its proper cell or pocket, and by inspection of which at any time all 25 information relating to the disposition of the car and its condition, whether empty or loaded, may be readily determined, also whether or not it has been properly routed. The accounting officials may therefore by 30 reference to the cabinet or rack ascertain at a glance the routing of any particular car, the date the same arrived on the line, whether the car was loaded or empty on its arrival, and whether or not the car has been 35 on the line for any unusual length of time, thus enabling the cars of foreign roads to be kept track of, as well as properly handled or routed, so as to facilitate the transportation, and at the same time avoid liability of undue 40 detention and shortage of cars by the reason of such unusual detention. At the end of every month's period the cards may be inspected and a report made indicating the 45 length of time each car remained on the line, so that prompt bills for per diem charges, etc., may be rendered, avoiding all claims for damages due to incorrect per diem accountings under ordinary systems. After each 50 foreign car has left the line, the card representing the same may be transferred to a second or temporary case for inspection for a certain time, and finally filed away permanently in a third case, which case may be of a similar character to the one disclosed, and 55 allowing any particular card to be found conveniently at any time. It will be apparent, of course, that the construction of cabinet cards employed by me enables the records to be kept in accurate manner and with a 60 minimum amount of time and labor, so that a vast saving is secured over the common practice of bookkeeping, as well as the trouble and labor of handling books, while the 65 number of accountants may be reduced and errors avoided.

I claim:—

1. Means for the use of railroads in keeping a record of the cars of foreign railroads upon its tracks, comprising a cabinet having pockets or cells arranged in numbered vertical and transverse rows, and cards adapted to be placed in said pockets or cells, each card having appropriately designated spaces to receive the number of a car, the name of the road to which it belongs, and other data 70 for indicating the routing and condition of the car, and a suitably designated space to receive a statement of per diem charges. 75

2. Means for use by railroads for keeping records of cars traveling on the tracks 80 thereof, said means comprising a cabinet having vertical and transverse rows of pockets, numerical indications designating the respective vertical and transverse rows of pockets, and cards adapted to be placed 85 within said pockets, each card having appropriately designated spaces to receive the number of a car, the name of the railroad to which it belongs, its routing, items pertaining to its disposition and condition, and 90 a statement of per diem charges.
